UNITED STATES PATENT OFFICE.

JAMES A. EDEN, JR., OF SPRINGFIELD, MASSACHUSETTS, ASSIGNOR TO WALTER H. FOSTER, OF NEW YORK, N. Y.

BOLT MACHINE.

Application filed December 6, 1920. Serial No. 428,456.

To all whom it may concern:

Be it known that I, JAMES A. EDEN, Jr., a citizen of the United States, and resident of Springfield, Massachusetts, have invented 5 certain new and useful Improvements in Bolt Machines, of which the following is a specification.

My invention aims to provide certain improvements applicable generally to machines 10 used in the making of bolts or the turning of bolt blanks and particularly useful in the manufacture of stay bolts for boilers.

The accompanying drawings illustrate an embodiment of the invention.

15 Fig. 1 is an elevation of one end of a stay bolt making machine, showing the particular unit thereof which is used for turning down bolt blanks, with my improvements applied thereto;

20 Fig. 2 is a side elevation of the same partly broken away;

Fig. 3 is a detail in elevation of the driving mechanism in Fig. 2;

25 Fig. 4 is an elevation of a blank produced in the machine illustrated;

Fig. 5 is a rear elevation, on an enlarged scale, of the mechanism shown in the upper part of Figs. 1 and 2;

30 Fig. 6 is a vertical section showing the feeding and necking mechanism on the plane indicated by the line 6—6 of Fig. 5.

The bolt blank produced by the machine has a shank 1 (Fig. 4) with enlargements 2 and 3 at the upper ends which are to be 35 threaded in other units of the machine, and has a button head 4 with a squared projection 5 on its end to be used in screwing the bolt into the plates of the boiler. It is desirable to form also a neck 6 between the 40 enlarged portion 3 of the blank and the face of the head 4, so that when the part 3 is threaded, the cutters will finish the thread sharply at the lower end without digging into the face of the head. The part 45 3 is sometimes finished with a tapered thread, of larger diameter at the lower end, and the bolts are varied in other ways from the particular design shown; my invention being applicable also to bolts of various designs.

The parts 2 and 3 of the blank are turned down accurately to diameter by means of 50 turning heads 7 and 8, which are set at fixed vertical distances on slides 9 traveling in vertical guideways on the inner faces of

the uprights 10 of the machine, which are mounted on a base 11. The slides 9 have their upper ends reduced to form rods 12 which pass up through the cross-head 13 and are pressed upwardly by means of 60 springs 14 bearing on the cross-head and engaging washers 15 fastened on the upper ends of the rods. These springs effect the retraction of the turning heads at the end of an operation. The parts are shown in 65 retracted position in Figs. 1 and 2, and in their advanced position in Fig. 6. The turning heads 7 and 8 are of any usual or suitable construction, and the head 8 is split and its forward half hinged at 16 so 70 that this half may be swung outward to permit removal of the blank.

The blank is rotated, the projection 5 on the lower end thereof fitting in a socket 17 which is rotated through suitable gearing 75 from a horizontal shaft 18 extending below the base 11. The shaft 18 through suitable intermediate gearing indicated at 19 drives a vertical shaft 20 which carries at an intermediate portion of its length a worm 21 80 (Fig. 3) which actuates a worm gear 22 which through suitable intermediate gearing drives a shaft 23 extending across between brackets 23^a on the backs of the upper ends of the uprights 10, and this cross shaft controls the feed of the turning heads. 85

On the central part of the shaft is mounted a sleeve having at one end a clutch member 24 (Fig. 5) adapted to be shifted to the right into engagement with a correspondingly toothed clutch member 25 on the shaft 23 and carrying a cam 26 which at the end of each revolution strikes a pin 27 and causes the sleeve to shift to the left, disconnecting the clutch and stopping 95 the revolution of the sleeve. The opposite end of the sleeve is engaged by a spring 28 surrounding the shaft 23 and reacting against the bearing 29 thereof to push the sleeve into clutched position. The stop pin 100 27 is pressed upward by a spring 30 and is pulled downward by hand or pedal through a link 31. This is an ordinary type of one-revolution clutch, and various other known types may be substituted therefor. 105 When the operator pulls down the stop pin 27 the sleeve is clutched in and the sleeve makes one complete revolution with the shaft and is then automatically unclutched, and the revolution of the sleeve 110

controls the feeding and retraction of the turning heads.

On the central part of the sleeve there is mounted a cam 32, Fig. 6, which bears 5 against a roller 33 mounted between a pair of arms 34 fixed on a hub 35 which turns on a short shaft 36 carried in brackets 37 on the backs of the side frames 10 of the machine. Mounted on the same hub 35 and 10 in the planes of the arms 34 are arms 38 which extend to points just inside of the slides 9 and are connected to the latter through links 39 to allow for lateral play.

At the beginning of the stroke the roller 15 33 rests on the smallest part 40 of the face of the cam. The rotation of the cam in the direction of the arrow operates through the roller 33 and arms 38 to feed the turning heads down quickly to engagement 20 with the work. The continued rotation of the cam feeds the heads downward continuously at a regular rate until the point 41 of the cam arrives at the point of contact with the roller 33. At this point the turning 25 operation is completed and the movement from here to the end 42 of the cam is a dwell during which the turning heads are held stationary, the rotation of the blank continuing. As the cam advances further, 30 the springs retract the cutter heads and the roller 33 is forced down to the starting point 40 of the cam, at which point the clutch is automatically opened, the machine stops and the operator withdraws the blank 35 and inserts a new one and presses the treadle to repeat the operation.

In order to form the neck on the blank, there is provided a necking tool or cutter 43 (Fig. 6) adapted to reciprocate in a tubular guide 44 fastened in the solid back of the turning head 7 and having a stem 45 pressed outward by means of a spring 46 bearing on the end of the tube 44 and against a head on the stem. On a bracket 47 mounted on the rear of the turning head is a transverse shaft 48 carrying a lever with a forked arm 49 embracing the outer end of the stem 45 and held between shoulders 50 and 51 mounted thereon. The opposite arm 50 52 of the lever is forked at its outer end and carries a pin 53 extending through a slot 54 in a link 55 of adjustable length connected at its upper end to one arm 56 of a lever whose other arm 57 is pressed 55 downward to pull up the link 55 and push in the necking tool at the proper time. The levers 56, 57 are mounted on a short shaft 58 carried in a bracket 59 mounted on one of the side frames 10 of the machine 60 as shown in Fig. 5. From this bracket 59 an arm 60 extends to a point under the arm 59 and carries an adjustable stop 61 (Fig. 6) which limits the downward movement of the arm 56 and the withdrawal of 65 the necking tool.

For actuating the arm 57 the same sleeve 24 which carries the cam 32 has a cylindrical hub on which is mounted a pin 63 adapted to engage a projection 64 on the arm, pressing the latter downward and the turning tool inward, holding it there for a determined short interval, say during six revolutions of the blank, and then riding over the cam shaped projection 64 and releasing the necking tool to permit its withdrawal 75 by the spring 45. The shape of the projection 64 is such that the necking tool will be pressed gradually inward to its full depth, held there for a moment and then released. To secure accurate timing of this 80 operation the projection 64 is made adjustable in the length of the arm 57. It is mounted on a stem 65 which is guided in a slot 66 in the arm, and can be set up with accuracy by means of a screw 67 and clamped firmly in position by a nut 68.

When the point 41 of the cam engages the roller 33 the lower turning head will have finished its work on the part 3 of the blank and the facing of the part 4. During the 90 downward feed of the head the pin 53 will move down in the slot 54, the link 55 being held up to the position shown by means of the stop 61. Excessive downward movement of the pin 53 while it is in the upper 95 part of the slot is prevented by means of a plate 69 on which the lower edge of the arm 52 rests. At the end of the downward feed the pin 53 will lie at the lower end of the slot 54. Therefore, as the pin 63 100 strikes the oblique face of the projection 64 the necking tool will be gradually advanced and held until the necking operation is completed and then withdrawn just before the end 42 of the cam passes its operative position, and the retraction of the turning head commences.

With the use of my improved machine it is possible in a single operation to turn the blank of the cylindrical or tapered form desired and to neck the end of this portion, thus turning out the finished blanks more expeditiously and cheaply than has heretofore been possible.

There are various other bolts provided 115 with necks and which can be economically manufactured with the aid of this machine with such modifications as are necessary to adapt it to the particular style of bolt in question. In referring to staybolts and the like, I include therefore various other bolts which have a portion of the blank near the head turned down and threaded.

Though I have described with great particularity of detail a specific embodiment of 125 my invention, yet it is not to be understood therefrom that the invention is restricted to the embodiment illustrated. Various modifications thereof in detail and in the arrangement of the parts may be 130

made by those skilled in the art without departing from the invention as defined in the following claims.

What I claim is:

- 5 1. A machine for turning headed stay-bolt blanks and the like including in combination means for rotating the blank, a turning head engaging a portion of the blank near the head thereof and movable lengthwise of the work, a necking tool carried by the turning head and means for feeding said turning head and advancing the necking tool.
- 10 2. A machine for turning headed stay-bolt blanks and the like including in combination means for rotating the blank, a turning head engaging a portion of the blank near the head thereof and movable lengthwise of the work, a necking tool carried by the turning head and means for feeding said turning head and advancing the necking tool, and maintaining it advanced for a determined interval after the advance of the turning head.
- 15 3. A machine for turning headed stay-bolt blanks and the like including in combination means for rotating the blank, a turning head engaging a portion of the blank near the head thereof and movable

lengthwise of the work, a necking tool carried by the turning head and means for feeding said turning head and advancing the necking tool, and means for withdrawing the necking tool on the retraction of the turning head.

30 35 4. A machine for turning headed stay-bolt blanks and the like including in combination means for turning down a portion of the blank near the head, feeding mechanism for said turning means adapted to cause a dwell in the feeding movement, the necking tool and means for advancing said necking tool and holding it advanced during a dwell in the feeding movement.

40 45 5. A machine for turning headed stay-bolt blanks and the like including in combination means for turning down a portion of the blank near the head, feeding and retracting mechanism for said turning means adapted to cause a dwell at the end of a feeding movement, a necking tool and means for advancing said necking tool and holding it advanced during the dwell at the end of a feeding movement and withdrawing it before the retracting movement.

50 55 In witness whereof, I have hereunto signed my name.

JAMES A. EDEN, JR.
